ELECTRIC JIG SAW TOOL

Nicholas Anton, Park Ridge, Ill.

Application May 1, 1956, Serial No. 41,291

Term of patent 14 years

(Cl. D93—3)

FIG. 1

FIG. 2

FIG. 3

FIG. 4

Fig. 1 is a side elevational view of an electric jig saw tool embodying my new design;

Fig. 2 is a top plan view thereof;

Fig. 3 is a front end elevational view as seen from the left-hand side of Fig. 1; and

Fig. 4 is a rear elevational view as seen from the right-hand side in Fig. 1.

I claim:

The ornamental design for an electric jig saw tool, substantially as shown.
